UNITED STATES PATENT OFFICE.

EDWARD B. HESS, OF NEW YORK, N. Y., ASSIGNOR TO ROYAL TYPEWRITER COMPANY, INC., OF NEW YORK, N. Y., A CORPORATION OF NEW YORK.

TYPEWRITING MACHINE.

1,424,905.

Specification of Letters Patent. Patented Aug. 8, 1922.

Application filed April 21, 1922. Serial No. 555,853.

To all whom it may concern:

Be it known that I, EDWARD B. HESS, a citizen of the United States, residing in Manhattan Beach, in the county of Kings, 5 New York, and State of New York, have invented certain new and useful Improvements in Typewriting Machines, of which the following is a specification.

This invention relates to the platens of 10 typewriting machines, and the object of the invention is to provide a supplemental or auxiliary platen which is associated with the main platen and which can be brought into service when multi-manifolding is desired 15 or when the main platen is not sufficiently hard or firm to produce multi-manifolds.

In my United States Patent No. 1,390,708 of Sept. 13, 1921, I have shown a typewriting machine in which the type action is such 20 as to reduce the noise caused by the impact of the type bars on the platen and in such machines it is customary to use a relatively soft cylindrical platen to assist in reducing noise. In these machines the number of 25 copies which can be produced is somewhat limited although sufficient for ordinary purposes. I have now provided an auxiliary platen so associated with the main platen that the latter may be used for ordinary service even though relatively soft and the former may be quickly brought into active position 30 when multi-manifolding is desired. In this way I am enabled to use a relatively soft platen either with or without a noise reducing type action for ordinary service where 35 only a few copies are required, but can quickly adapt the machine for multi-manifolding without removing the main platen or in any way modifying the mechanism.

40 In carrying out my present invention I make little or no change in the construction of the main platen or in the construction of the platen carriage or in other parts of the machine. In the preferred construction, the 45 auxiliary platen is in the form of a strip of rigid material preferably metal, which extends from end to end of the main platen and is mounted to turn to a limited extent about the longitudinal axis thereof either 50 relatively to the main platen or simultaneously with it. The auxiliary platen at all times lies close to the surface of the main platen from end to end thereof so that when

in active position, the main platen provides a firm backing for the auxiliary platen, which latter has smooth inner and outer sides conforming to the shape of the main platen. By a simple operation the auxiliary platen may be brought from an inactive to the active position or vice versa, and in order to 55 hold the auxiliary platen in either position I provide detent mechanism of novel construction. The auxiliary platen is held in such close contact with the main platen that the former may be turned with the latter so that when 60 the auxiliary platen is released from its detents it may be moved to active position by turning the main platen by means of its hand pieces or knobs, the friction between the two platens being sufficient to cause such 65 movement. But the auxiliary platen may, if desired, be moved independently of the main platen. The construction of the auxiliary platen is such that it may be used as 70 an erasing plate if desired and it may be 75 formed with a letter space scale. Means is provided for preventing overthrow of the auxiliary platen when moved in either direction and provision is made for limiting the 80 movement of the detent pawls and for causing the strain of the detent springs to be taken by the frame of the machine when the 85 pawls are engaged with the detent members of the platen. Other features of the invention will be hereinafter explained.

In the accompanying drawings:—

Figure 1 is a view on a large scale and in vertical section of the main platen with the associated auxiliary platen. Some usual or ordinary parts of a typewriting machine are 90 also shown by way of illustration. The manner in which a large number of sheets for manifold purposes may be passed over the auxiliary platen is illustrated by the wide black line.

Figure 2 is a sectional view taken at the right hand end of the platen, the auxiliary platen being locked in an active position.

Figure 3 is a similar view, the section being taken near the left hand end of the 100 platen, the auxiliary platen being locked in inactive position.

Figure 4 is a view of the platens partly in plan and partly in section and with parts broken away showing how both members of 105 the detent mechanism are connected with the

platens. This figure of the drawings shows certain fractional spacing devices which form no part of the present invention.

Figure 5 is a front view of a typewriter carriage carrying an ordinary platen and with the auxiliary platen shown in an active position across the line of print.

Figure 6 is a perspective view of the detent pawls employed at opposite ends of the 10 platen and which are connected to move coincidentally.

Figure 7 is a perspective view showing 15 how the auxiliary platen is mounted to turn about the longitudinal axis of the main platen and how it is provided with detent members for co-operation with the detent pawls.

Figure 8 illustrates how the auxiliary platen may be provided with a letter space scale.

20 Figure 9 shows the auxiliary platen in an inactive position with a type bar printing in the usual way with the main platen only as a backing.

In Figures 1 and 2, the type bar is shown 25 as being connected to a noise reducing type action of the kind shown in my patent above mentioned, while in Figure 9 the type action is different. My improvements may be used in either type of machine.

30 Most of the mechanism shown aside from the auxiliary platen and its detent mechanism is similar to that shown in most Royal machines. The main cylindrical platen A is mounted in a carriage side frame—pieces of 35 which are indicated at B. The rail b of the carriage is supported by a shift rail C as usual and the type bars D are pivotally connected with a segment E and are operated by pull links d in the manner described in

40 my patent of Sept. 13, 1921 or in the usual way. A type bar guide is indicated at F, a ribbon guide or vibrator at G and paper feed mechanism at H. The upper feed rolls I are supported by rocker arms i as heretofore. In Figure 5 a centrally located scale J of usual construction is shown as are also end scales K. The features of construction above described are not important so far as my present invention is concerned. I

50 have merely illustrated them to indicate how my improvements are associated with an ordinary cylindrical platen and parts of the mechanism immediately associated therewith. The main platen A may be of 55 the usual construction, being cylindrical in form with a core a covered with rubber or other relatively soft material a'. The platen shaft a² extends through the side plates of the carriage and is provided with finger pieces or knobs a³ as usual. The right hand end of the platen has secured to it a circular plate M formed with a boss m, the end of which abuts the adjacent side piece B of the carriage. The platen shaft extends 60 through the plate M and through the boss 65

and also through an opening in the plate B and carries on its outer portion a sleeve m' having a reduced inner portion m² entering the hole in the side plate B. It will be observed by reference to Figure 4 that the 70 outer end of the boss is formed with an annular shouldered recess m³. This is for a purpose hereinafter described. The opposite or left hand end of the platen carries fractional line space mechanism of all 75 known construction comprising among other things a cylindrical member n turning at all times with the platen and a member n' associated with devices for controlling the spacing of the lines of print. 80

The auxiliary platen O is in the form of a narrow strip of suitable rigid material, such as metal, and extending from end to end of the main platen and curved transversely to correspond with the contour of the main 85 platen so that it may lie close thereto and in frictional contact therewith at all times throughout its entire length and from its upper to its lower edge. Both the inner and outer surfaces of the auxiliary platen are 90 smooth in order that good sharp type impressions may be made and that it may be moved when desired around the axis of the main platen but independently thereof.

The auxiliary platen is so mounted that it 95 may turn with the main platen about the longitudinal axis thereof from inactive to active position or vice versa while in close contact with the main platen or may move about such axis independently of the main 100 platen. Novel means is provided for limiting the movement of the auxiliary platen in either direction and for locking it at the limits of its movements.

At the right hand end of the main platen 105 I provide a support Q for the auxiliary platen comprising a dished central portion q formed with a lateral extension q' carrying an arm q² to which the inner bent portion o at the right hand end of the auxiliary platen is secured. The central portion q of the support is provided with a central opening q³ which surrounds and is seated in the groove or recess m³ formed in the outer end of the boss m. As shown in Figure 4 110 the support Q is mounted to turn between the grooved shouldered portion of the boss and the adjacent side plate of the carriage, at the same time preventing lateral displacement of the auxiliary platen. 115

The opposite end of the auxiliary platen has an inturned end portion o' secured to a ring R which is mounted to turn about the axis of the main platen while supported between the members n and n'. The specific 125 supports for the auxiliary platen shown are not essential but they have been found serviceable in applying the invention to a machine of the Royal type.

The auxiliary platen is held throughout 130

its entire length close to the main platen and as hereinbefore described may be either turned with the main platen or independent thereof. It is important that suitable 55 detent mechanism be provided to hold the auxiliary platen in the position to which it is set and for this purpose I have provided devices which have been found to be most efficient in practice. The support Q, it will 10 be observed, is formed with a peripheral portion having a curved edge q^4 concentric with the axis of the platen and at opposite ends of which are formed notches x, x' to receive a detent pawl. The ring R on the 15 opposite end of the platen is formed with notches y, y' for a similar purpose.

Preferably two detent pawls T and T' are employed, one of which co-operates with the 20 detent member Q and the other with the detent member R. Preferably these pawls are connected by a horizontally arranged rod U extending across the machine beneath the paper table. The pawls are so mounted that they are always moved simultaneously 25 and to the same extent. The opposite ends of the rod U are preferably mounted to turn in ears b' extending upwards from the carriage side plates, but other means for supporting the rod may be provided. The rod 30 may be so mounted as to be a permanent part of the machine carriage or it may be detachably connected therewith, although preferably the rod with its detent pawls are made a permanent part of the machine as 35 they do not in any way interfere with other portions of the mechanism.

The pawls T, T' have teeth t, t' formed on their front ends adapted to engage the notches x, x', y, y' and they are formed with 40 projections or stops t^2 which strike against the top edges of the side plates and thus limit their downward movement while engaging the notches. Springs W tend to draw the toothed ends of the pawls downwardly until the downward movement is arrested by the stops t^2 above referred to. The upward movement of the pawls may be limited by a stop t^3 formed on one of the 45 pawls or on both of them if preferred. A handle or finger piece for lifting the pawls simultaneously is indicated at V. This is 50 preferably placed at the left hand side of the machine so that the hand of the operator may be applied to the knob or finger piece a^3 at the right hand side of the machine to turn the main platen, while the left hand of the operator raises the pawls simultaneously to permit the main platen to be turned to 55 bring the auxiliary platen into active or inactive position.

While the auxiliary platen is being moved from one position to another, the pawls ride on the curved portions q^4 and r of the supports between the detent notches. When the 60 pawls engage in the notches they lock the

mechanism firmly and in such manner as to hold the auxiliary platen with precision close to the main platen throughout its entire length so that a firm and rigid backing is provided for manifold purposes. If the 70 auxiliary platen were allowed to shake or to spring back and forth on the main platen, good printing results could not be obtained. It will be observed by reference to Figure 2 that the front and rear walls of the notches 75 x, x' and by reference to Figure 3 that the front and rear walls of the notches y, y' are straight and parallel and when in active position are tangential to the axis of the main platen. The walls of the teeth on the 80 detent pawls are similarly shaped so that when the pawls are engaged in the notches no movement of the auxiliary platen can take place, but the main platen is free to turn in the usual way. Without positive 85 locking means of this sort the main platen could not be turned without moving the auxiliary platen in view of the close contact of the auxiliary platen with the main platen which I have found to be a most desirable 90 feature of the invention.

In order to limit the movement of the auxiliary platen, i. e., to prevent overthrow in either direction, the support Q is formed with a projection z which strikes against the 95 end of the pawl T when the limit of the backward movement is reached. The support Q is also formed with a projection z' which serves a similar purpose when the limit of the forward movement is reached. 100 These projections are disposed close to the notches x, x' and serve as locators for the auxiliary platen.

The details of the type action are not illustrated in the drawings. As before stated, 105 noise reducing type actions of the kind indicated in Figures 1 and 2 may be employed or the ordinary type action like that shown in Figure 9 may be used.

The auxiliary platen may conveniently be 110 used as an erasing plate being moved to any desired or convenient position on the main platen for this purpose.

In Figure 8 I have shown an auxiliary platen provided with a letter space scale 115 which may be conveniently used in many kinds of work, especially in work of the kind known as "split billing."

While the auxiliary platen is held very close to the main platen, it is made so thin, 120 light and smooth and is made to conform so closely to the shape of the main platen that when the auxiliary platen is in use or when not in use it does not act unduly as a brake to the main platen or in any way interfere 125 with its normal movement. It can in an instant be brought into active position or withdrawn therefrom.

In some of the following claims where reference is made to a platen in the combi- 130

- nation specified, it is understood that the platen includes not only the striking surface but also other parts of the platen which are movable therewith.
6. No claim is made herein to the combination with a soft cylindrical platen for general service, of a noise-reducing type action and an auxiliary platen of relatively hard material adapted to be held in the line of print for multiple manifold purposes, as such subject matter is covered by several claims to this broad feature and amplifications thereof in my application for patent filed June 22, 1922.
10. I claim as my invention:—
1. An auxiliary platen for typewriting machines, comprising a strip of suitable rigid material co-extensive in length with that of the main platen, and curved on opposite sides to conform to the curvature of the main platen, in combination with supports at its ends for holding it to turn about the longitudinal axis of the main platen while in contact therewith and which are provided with detent devices.
2. An auxiliary platen for typewriting machines comprising a strip of suitable rigid material conforming in length and curvature with the main platen and having smooth inner and outer sides in combination with supports at its ends for holding it in frictional engagement with the main platen to turn about the longitudinal axis thereof, either with the main platen when the latter is turned, or independent thereof.
3. In a typewriting machine the combination of a cylindrical platen, an auxiliary platen held in frictional engagement therewith and movable therewith and thereby about its axis and also movable independently thereof, and means for locking the auxiliary platen in active and inactive positions and for preventing overthrow beyond these positions.
4. In a typewriting machine, the combination of the main cylindrical platen, and an auxiliary platen comprising a strip of suitable rigid material co-extensive in length and curvature with that of the main platen, and having smooth inner and outer sides in combination with supports at its opposite ends for holding it to turn about the longitudinal axis of the main platen, one of said supports having a curved peripheral portion with detent notches at opposite ends adapted to engage a detent pawl.
5. An auxiliary platen for typewriting machines, comprising a strip of suitable rigid material, co-extensive in length with that of the main platen and curved on opposite sides to conform to the curvature of the main platen, in combination with supports at its ends for holding it to turn about the longitudinal axis of the main platen and which are provided with connected detent devices in alignment with each other at opposite ends of the platen.
6. In a typewriting machine the combination of the main cylindrical platen, an auxiliary platen mounted to turn about the longitudinal axis thereof and provided with detent members, detent pawls, pivotally mounted in rear of the platen and adapted to engage the detent members thereof, and means connecting the pawls at opposite sides of the machine whereby they may be simultaneously lifted.
7. In a typewriting machine, the combination of a main cylindrical platen, an auxiliary platen mounted to turn about the longitudinal axis thereof, detent members connected with the opposite ends of the auxiliary platen, detent pawls pivotally mounted in rear of the platen and provided with springs for drawing them towards the detent members of the platen, means for limiting the movement of the pawls after engagement with the detent members of the platen and means for simultaneously raising the pawls.
8. In a typewriting machine, the combination of the main cylindrical platen, an auxiliary platen mounted to move about the longitudinal axis thereof, detent members at opposite ends of the auxiliary platen, detent pawls adapted to engage said detent members, a connection between the two pawls and means for limiting the movement of the pawls when they are withdrawn from engagement with the detent members of the platen.
9. In a typewriting machine, the combination of the main cylindrical platen, an auxiliary platen mounted to turn about the longitudinal axis thereof, a detent member at one end of the platen, having detent notches formed with tangential walls, and a detent pawl adapted to engage said notches, having front and rear walls corresponding with those in the notches in the detent member of the platen.
10. In a typewriting machine, the combination of a main cylindrical platen, an auxiliary platen mounted to turn about the longitudinal axis thereof, a detent member at one end of the platen formed with notches for locating the active and inactive positions of the auxiliary platen, and a pawl having a toothed front end adapted to closely fit either of said notches with its front and rear walls conforming to the front and rear walls of said notches, and projection on the detent member adapted to engage said detent pawl to limit the movement of the auxiliary platen, when turned about the axis of the main platen.
11. In a typewriting machine the combination of a main platen, an auxiliary platen associated therewith and movable to active and inactive positions, said auxiliary platen

being provided with letter space scale graduations for the purpose specified.

12. An auxiliary platen for typewriting machines, comprising a strip of suitable rigid material co-extensive in length with that of the main platen and curved on opposite sides to conform to the curvature of the main platen and which is provided with a margin locating scale and with supports 5 at its ends for holding it to turn about the longitudinal axis of the main platen from a position in rear of the axis of the platen to a position across the line of print.
13. In a typewriting machine, the combination of a main cylindrical platen and an auxiliary platen associated therewith and frictionally held thereby in a plurality of 10 positions, said auxiliary platen having a smooth outer surface and being movable 15 about the axis of the main platen from a

position in which it serves as a backing during manifolding to another position in which it serves as an erasing plate.

14. In a typewriting machine, the combination of a main platen and an auxiliary 20 platen associated therewith and movable thereby to active and inactive positions relatively to the printing point.

15. In a typewriting machine the combination of a main platen and an auxiliary 25 platen associated therewith and movable thereby to active and inactive positions relatively to the printing point, means for holding the auxiliary platen in active position, and devices for preventing overthrow of the 30 auxiliary platen when moved from one position to the other.

In testimony whereof, I have hereunto 35 subscribed my name.

EDWARD B. HESS.
